MERCHANTISING PACKAGE

William A. Ringler, Wayne, Pa., assignor to National Folding Box Company, New Haven, Conn., a corporation of New Jersey

Application September 21, 1935, Serial No. 41,526

8 Claims. (Cl. 266—56)

This invention relates to a merchandising package and more particularly to a package for a plurality of articles, each article being separately and individually dispensed by the merchant by separating the package into predetermined article-containing segments when a customer calls for one of the articles.

Heretofore it has been customary to dispense merchandise, such as electric light bulbs, radio tubes, batteries, spark plugs and other small articles separately in individual containers. Such containers are generally susceptible of being opened, the good article removed, an inferior or worthless article substituted, and the container again closed without leaving any exterior evidence on the container that the original contents have been removed or tampered with. The reputable manufacturer of merchandise naturally desires to deliver to the actual user his merchandise in as good condition as when it left the factory, and above all, to prevent spurious merchandise being passed off in his containers as his own. Individual containers heretofore used, due to their multiplicity, are also expensive to pack, store and handle and greatly increase the cost of taking stock inventory due to the fact that each item must be separately counted and often inspected to make sure that the container contains the proper article in good condition.

It is one of the objects of this invention to overcome the deficiencies of merchandising containers above noted and to provide a package containing a plurality of articles which can be handled, stored and inventoried as a unit, but which can be easily broken or separated into predetermined segments, as the merchant sells the same to a customer, each segment containing one or more articles.

Another object of this invention is to provide a merchandise package in "stick" form which can be broken into segments by the merchant to individually dispense the article contained in each segment as the customer calls for it, said package being constructed and sealed as to prevent unauthorized removal of the contents contained therein.

Another object of this invention is to provide a sealed container for merchandise from which the contents cannot be removed without leaving visible evidence of tampering.

Still another object of this invention is to provide an improved container for electric light bulbs, radio tubes and similar articles liable to injury from shock having means for supporting the article in spaced relation to the side walls

of the outer container so that shock delivered to the outer container will not be transmitted to the article.

Another object of this invention is to provide an improved container for light bulbs, radio tubes, batteries and similar articles requiring test examination before delivery to the customer, in which the article may be sealed against unauthorized removal and yet provision made to permit ejection of the test end of the article so that the desired test can be performed prior to sale and delivery of the article to the customer.

Another object of this invention is to provide an improved method and apparatus for sealing the merchandise packages herein disclosed.

Other objects of this invention will become apparent as the disclosure proceeds.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 shows a blank of paperboard suitably cut and scored to form the outer container portion of the merchandise package;

Fig. 2 shows a blank which has been suitably cut and scored to provide an inner container or sleeve for the article merchandised;

Fig. 3 is a perspective view of the inner container or sleeve assembled from the blank shown in Fig. 2 showing, for purpose of illustration, an electric battery positioned therein;

Fig. 4 is a perspective view of a plurality of inner containers with a battery contained in each, said inner containers being arranged in juxtaposition and about to be surrounded and enclosed by the glued outer container forming blank shown in Fig. 1;

Fig. 5 is a perspective view of the merchandising package as completely assembled, a segment of said package being shown partially severed to illustrate how the individual articles may be separately and individually delivered by the merchant to the customer;

Fig. 6 shows a paperboard blank suitably cut and scored to form an outer container of somewhat modified form;

Fig. 7 is a perspective view of the blank shown in Fig. 6 completely assembled and enclosing a plurality of electric light bulbs each individually contained in an inner protective shell or sleeve;

Fig. 8 is a fragmentary perspective view of the assembled outer container illustrating particularly how the same can be closed and sealed to prevent unauthorized opening of the container;

5 Fig. 9 is a transverse cross sectional view through the fully assembled merchandising package, this view being taken on line 9—9 of Fig. 7;

Fig. 10 shows a blank from which an outer container of further modified form may be made;

10 Fig. 11 is an exploded perspective view of the merchandising package, this view showing particularly a plurality of aligned inner protective shells each containing an electric light bulb with an outer container forming blank shown in Fig. 18, partially surrounding the same;

15 Fig. 12 is a perspective view of the fully assembled merchandising package assembled from the parts shown in Fig. 11, one segment of the package being partially severed from the remaining portion of the package and other parts being 20 broken away to more clearly illustrate the construction;

25 Fig. 13 shows a blank which has been suitably cut and scored to provide an inner cushion supporting member for a plurality of delicate articles, such as light bulbs and the like;

30 Fig. 14 shows a blank from which an outer container may be made, this outer container being used to surround and enclose the cushion supporting member formed from the blank shown in Fig. 13;

35 Fig. 15 is a fragmentary perspective view of the cushion supporting member formed from the blank shown in Fig. 13 about to be inserted into the outer container formed from the blank shown in Fig. 14, certain parts being broken away to more clearly illustrate certain features of the construction;

40 Fig. 16 is a transverse cross sectional view of the merchandising package as it appears when fully assembled and sealed;

45 Fig. 17 is a perspective view of an improved apparatus for gluing and permanently securing the inner containers or sleeves to the outer container;

50 Fig. 18 is an enlarged transverse cross sectional view through the upper gluing arms taken along lines 18—18 of Fig. 17, this view illustrating more particularly the manner in which the glue is applied to the inside face of the outer container;

55 Fig. 19 is an enlarged fragmentary cross sectional view through one of the gluing arms of the apparatus, this view being taken on line 19—19 of Fig. 20;

60 Fig. 20 is an enlarged fragmentary face view of one of the gluing arms showing particularly the glue escape opening and the automatic closure therefor, this view being taken on line 20—20 of Fig. 18; and

65 Fig. 21 is a diagrammatic view of a gluing apparatus of somewhat modified form which can be used to apply glue to the outside faces of the individual inner containers.

Similar reference characters refer to similar parts throughout the several views of the drawings and the specification.

70 The merchandise package shown by example in Fig. 5 comprises a plurality of individual inner containers or sleeves each formed from a blank A, shown in Fig. 2, and an outer container enclosing a plurality of aligned inner containers formed from the blank B, shown in Fig. 1. The inner container blank, shown in Fig. 2, comprises side wall forming portions 1 defined by score lines 2 and a securing tab portion 3 which may

be fixed by glue or other means to the opposite side wall portion to provide a tubular member or sleeve. For purpose of illustration, there is shown in Fig. 3, a small battery T contained therein. It is understood, however, that the inner containers are so designed and shaped as to conveniently fit the article.

5 The blank B which forms the outer container, is traversed by a plurality of parallel extending perforations 6 which define lines of weakness or lines of separation to permit separation of the blank B when assembled in container form into separate individual article-containing segments. Each segment comprises the side wall portions 5 and 7, the end wall portions 8 and 9 and the securing tab portion 10 all defined by parallel extending score lines 11. In assembling the package, the inner containers each containing an article of merchandise T are arranged in a row, as shown in Fig. 4. Glue g may be applied 20 to the inside faces of the side walls 5 and 7 and to the outside face of the securing tabs 10. The blank B may then be wrapped or folded around the aligned inner containers so that the glued inside faces of the side walls 5 and 7 will adhere 25 to opposite side walls 1 of the inner containers and the securing tabs 10 will overlap and adhere to the side walls 7 of the outer container, thus forming a tubular member or sleeve within which the aligned inner containers are housed and secured. The outer container or blank should be applied in such a manner that the perforated lines of weakness or lines of separation 6 substantially coincide with the line of division between the individual inner containers so that 35 when the lines of weakness 6 are broken to separate the segments, an inner container will be neatly housed within the outer container segment, as illustrated in Figure 5. It will be noted that the articles contained within the finished 40 package and also the individual articles contained in the separated segments are completely sealed and enclosed against unauthorized removal. The end portions 8 and 9 of the outer blank serve to seal and close the ends of the tubular inner 45 container. When the articles are thus packaged it is impossible to remove the article without tearing or defacing the container forming parts and thus leave visible evidence of tampering. A sealed and substantially foolproof package for a 50 plurality of articles comprising sealed and substantially foolproof segmental containers for individual articles is thus provided.

To facilitate separation and division of the merchandising package into separate individual 55 container segments it has been found helpful to actually cut through the material of the outer container at one or two adjacent corners as at 14. These cuts are sufficient to permit the merchant to continue the separation of the segments along the lines of weakness 6 without difficulty. The merchandising package, however, can be handled as a unit and can easily contain from six to ten or twelve or even more separate articles as found convenient. The merchandising packages or units are sufficiently strong and rigid so that they can be handled, packed and stored without danger of the separate article containing segments breaking off. When stock inventory is taken the separate units only need be counted and the total number of separate articles can be determined by multiplying the number of package units by the number of unit articles each package contains. A convenient, eco- 70 75 80 85 90 95

nomical, sealed and substantially foolproof merchandising container is thus provided.

Should it be desirable or necessary to test the article contained in the merchandising package 5 prior to sale to a customer, the outer segmental end walls 8 may be individually provided with a suitable opening 12 opposite the test end *t* of the article *T* contained therein. If desired, an opening 13 may be provided in each of the opposite 10 end wall segments 9 through which an instrument, such as the finger, may be inserted to eject the test end *t* of the article through the opening 12 a sufficient amount to perform the test. It is understood that in the case of batteries, electric 15 light bulbs, radio tubes and similar electrical devices having test or contact ends, a suitable electric button or socket connected in an electric circuit is provided with which the test end of the article is placed in contact. An effective and 20 highly efficient merchandising package, highly adaptable to all requirements, is thus provided.

Where articles, such as electric light bulbs, are to be packed in the container, it may be advisable to provide suitable means to protect the 25 bulb or delicate articles liable to injury from shock, by a suitable cushion means. There is shown in Fig. 7, for purpose of illustration, a somewhat modified form of merchandising container especially adapted for the merchandising of electric light bulbs and similar delicate instruments. The bulb *L* is contained and housed in a tubular sleeve 20 preferably formed of so-called corrugated paperboard and whose side walls will absorb exterior shock. The outer blank *B*₁ is 30 similar to the blank *B* shown in Fig. 1, except in certain details as will be presently brought out. In packaging the bulbs, a plurality of corrugated bulb-containing sleeves 20 are aligned in a row. The outer container blank *B*₁ is then wrapped 35

40 around the corrugated inner sleeves 20 and the securing tabs 10 placed in overlapping position against the outside face of the side wall segments 7. The end wall segments 8 and 9 are each provided with a cut line 24 defining a tab 21 45 which hinges along the score line 11. When the outer container has been wrapped around a plurality of inner tubular sleeves 20, as above described, the tabs 21 can be folded inwardly against the adjacent inside face of the corrugated sleeves 50 20, as clearly shown in Figs. 7 and 9. A staple 23, a rivet, a line of stitching or other permanent securing means may then be stitched through each hinged tab 21, the securing tab 10 and the intermediate side wall 5 and/or the intermediate side wall of the corrugated shell 20 55 so as to permanently seal and lock the inner tubular sleeve within the outer container. The inner tubular sleeves 20 are arranged in the outer container in such a manner that the lines of separation 6 in the outer container substantially coincide with the lines of division between the adjacent inner shells 20. Separation of the merchandising package into individual segments can be facilitated as heretofore suggested by providing cut lines 14 which extend through the material of the outer container at one or more corners. The openings left by the removal of the tabs 21 from the end walls 8 and 9 can be used to facilitate and permit ejection of the test 60 end *t* of the bulb. It will be noted that any shock delivered to the side walls of the outer container will be to a large extent absorbed by the inner corrugated shell and will not be transmitted to the delicate bulb *L*. The bulbs are preferably 65 alternately arranged in reverse position within

the package, as shown in Fig. 7, to further reduce the possibilities of breakage.

A further modified merchandising package for electric light bulbs and similar articles liable to become damaged from shock is illustrated in Fig. 12. The inner containers or sleeves 20 are formed from shock absorbing corrugated paperboard and each is adapted to contain a single light bulb *L*. The outer container forming blank *B*₂, as shown in Fig. 10, is substantially similar to the outer container forming blank *B* shown in Fig. 1. The blank *B*₂ may be wrapped around a plurality of aligned inner article-containing sleeves 20 in the manner heretofore described, or the blank *B*₂, 10 may first be assembled into tubular form by gluing the securing tabs 16 to the opposite side wall 7, and thereafter telescoping the individual inner article containing sleeve 20 into the outer container or sleeve. 15

If desired, a continuous line of weakness 27 defining a punch out area 26 may be provided in the end wall portions 8 and 9. When the individual article is to be tested, the portions 26 may be punched out to permit ejection of the test end *t* of the bulb. The merchandising package 20 may be separated into one or more individual article-containing segments by the merchant at the time the customer calls for one or more of the articles. The inner tubular sleeves or shells may be fixed to the outer container by 30 means of strips of glue *g* deposited on the inside face of the outer container either before the blank is assembled into container form or after the inner tubular sleeves have been positioned within the assembled outer container. An improved apparatus for gluing and securing the inner containers or sleeves within the outer container will be described hereafter. 35

There is shown in Figs. 15 and 16 a merchandising package of further modified construction 40 so designed as to cushion the articles contained therein against shock. It is therefore especially adapted for the packaging of electric light bulbs, radio tubes and other delicate instruments of different sizes. This container comprises more particularly an inner article-supporting member *A*₃ which is telescoped into an outer container-forming sleeve *B*₃ formed from the blank shown in Fig. 14. The inner article-supporting member is traversed by a plurality of parallel extending 45 perforated lines of weakness 34, each defining a separable segment supporting an individual light bulb *L*. The individual segments each comprise spaced leg portions 30 and 31 and a hammock portion 32 hinged to the leg portions along the score lines 33. When assembled the leg portions 30 and 31 are placed in erect vertical position as shown in Figs. 15 and 16 and the hammock portion 32 sags therebetween. The lower portion *l*₁ of the bulb *L* is preferably inserted through a suitable opening in the hammock portion which is formed by providing a pair of parallel cut lines 36 and 37, and a transverse cut line 38 connecting the cut lines 36 and 37. These cut lines define a pair of ears 39 which can be forced 50 downwardly so as to provide an opening therebetween. The ears 39 are so shaped and arranged that they will frictionally grip the socket end *l*₁ of the bulb *L* and thus securely retain the bulb within the support member. 55

The outer container formed from the blank *B*₃ shown in Fig. 14 is assembled in tubular form by overlapping the securing tab 10 over the end wall 9, and securing the parts together by glue or other permanent securing means. The outer 60

blank B₃ assembled into tubular form as shown in Fig. 15, receives the inner supporting member having the bulbs L mounted therein. It will be noted that the legs 30 and 31 of the inner supporting member are of sufficient height to snugly fit within the outer tubular container and the outside face of the legs 30 and 31 is surfaced with glue which will adhere to the inside face of the side walls 5 and 7 of the outer tubular container 10 to permanently seal the parts together. The inner support member is positioned within the outer tubular member so that the lines of weakness 34 traversing the inner support member substantially coincide with the lines of weakness 6 15 which traverse the outer container. To facilitate separation of the merchandising package into separate article-containing segments, it may be desirable to provide a cut line 35 which extends through the material of the hammock portion 32 as clearly shown in Figs. 13 and 15. It may be desirable to similarly provide a cut line 14 which extends across the end walls 3 of the outer container. The individual segments can then be easily broken off by the merchant by applying a 20 slight bending pressure to the package, or if necessary, a simple knife or similar tool can be provided to effect the separation.

The container above described is remarkably adapted for the packaging of electric light bulbs 25 and especially light bulbs of small dimensions such as are used for automobile lighting. It will be noted that the hammock portion 32 cushions and suspends the bulb L away and out of contact from the surrounding walls of the outer container. No shock short of an actual puncturing of the walls of the outer container can contact or be injuriously transmitted to the delicate bulb contained therein. The projecting ears 39 grip the lower end L₁ of the bulb with a firm friction 30 so that the package can be placed upside down or in any position without causing the bulb to leave its proper seat within the hammock portion.

The merchandising containers herein described can be economically manufactured on automatic machinery in common use. The blanks forming 45 both the inner and outer containers can be cut and scored in a single operation on a cutting and scoring machine. The gluing operations can also be performed automatically. It will be noted 50 that the blanks used are rectangular in exterior outline and there is no waste of paperboard material. The novel merchandising packages herein presented are more economical to manufacture and assemble than merchandising containers 55 heretofore provided for this purpose. In addition, the packages herein presented are substantially foolproof in that they prevent unauthorized removal of or tampering with the contents, they permit quick and ready test and examination of 60 the articles without necessitating the removal thereof, they can be more economically handled, packed, stored and inventoried than containers heretofore provided, and the individual articles contained in the package units can be quickly 65 severed and removed from the package by the merchant and delivered to the customer in individual sealed container segments which provide all the security and protection features which a separate individual container could possibly 70 possess.

There is shown in Figs. 17 to 20, inclusive, a novel and improved apparatus for applying glue or other adhesive to secure the inner and outer containers together in sealed relationship. The 75 apparatus more particularly comprises spaced

hollow arms or tubes 51 and 52 applicable to one side of the package, and spaced arms 53 and 54 applicable to the other side of the package. The arms are hollow so as to freely permit the flow of glue therethrough and are preferably elliptical or 5 rectangular in shape so that they can easily be inserted between the outer container and the inner containers, as shown in Figs. 17 and 18. A glue escape opening 59 is provided preferably in the outside face of each arm through which the 10 glue feeds on to the inside faces of the outer side walls 5 and 7 of the outer container. A suitable slide closure 61 is arranged to slide across the glue discharge opening 59. The slide closure 61 is mounted for sliding movement upon suitable 15 spaced studs or rivets 64 secured to and preferably within each arm. The studs 64 extend through suitable slots 65 in the slide closure 61 to guide the closure into sliding movement across the opening. The closure 61 is limited in its 20 sliding movement by a friction button 62 which extends through and engages the opposite ends 71 and 72 of the opening 59. The closure 61 is normally held in position to close the discharge opening in the glue arms by means of spring elements 66 one end of which is secured to the closure 61 and the other end to a fixed stud 67 extending from the arm. Figs. 19 and 20 show the closure 61 as completely closing the opening 59, the friction button 62 then abutting the edge 72 30 of the opening. The closure 61 and associated apparatus is preferably mounted within the hollow tubular arm and is so arranged and adjusted that when the arms are inserted into and between the outer and inner containers the closure 35 will seal and close the discharge opening 59 in the arms and prevent the escape of glue therefrom. When the arms are withdrawn from the package, however, the button 62 will frictionally engage the outer container side walls 5 and 7 40 and cause the closure to drag or lag against the action of the coil spring 66 until the button engages the opposite edge 71 of the opening in which position the closure 61 will partially uncover the opening and permit the escape of 45 glue therefrom. The button 62 will also act to smear or distribute the glue over the wall surface. After the glue arms have been removed from each package, the packages are stacked one upon the other so as to press the glued inside 50 faces of the side walls 5 and 7 of the outer container into adhesive contact with the side walls of the separate inner containers 20. The inner containers are thus firmly and permanently glued and united to the outer container. 55

The glue arms 51 and 52 on one side of the container and arms 53 and 54 on the other side of the container may be supplied with glue from a suitable fountain or receptacle 57 supported on a bracket 58. The glue flows from the receptacle 60 57 through the supply pipe 56 into the hollow cross arm 55 and thence into the glue arms above described. It is understood that the glue arms are preferably arranged in a tilted position so as to facilitate the flow of glue to the outer ends 65 thereof. The glue arms 51, 52, 53, and 54 are made quite flat and knife-like in cross section, so that they can be easily inserted between the inner and outer containers without requiring any substantial distortion, stretching or compression 70 of the inner or outer containers. It is understood that Figs. 18, 19 and 20 show an outer container which is distorted way beyond that which would occur in actual practice but this has been done to permit enlargement of the glue arms to more 75

clearly illustrate the construction of the automatically operated glue release closure and associated devices.

There is shown in Fig. 21 a diagrammatic view 5 of a modified form of glue applicator especially adapted to coat the outside surfaces of the inner container or sleeve 20 with glue either before or after the insertion of the bulb L or other article therein. In this device glue applicator rolls 14 10 are rotatably mounted upon suitable spindles 14 rotatably supported by trunnions 15 extending from the side walls of the glue box 10. Feed rollers 11 rotatably mounted upon spindles 12 fixed to the side walls of the glue box 10 are positioned 15 to rotate in a lake of glue g poured into the glue box. The feed rolls 11 pick up the glue and deposit a film of glue upon the glue applicator roll 13 with which they are in constant peripheral contact. The applicator roll 13 when rotated in 20 turn applies the glue film deposited thereon on to the outside face of the inner container 20 as clearly shown in Fig. 21. The applicator roll 13 is suitably spaced to permit the proper insertion of the container 20 to be glued therebetween. A suitable 25 crank or other device connected to the rollers 11 and 13 by a suitable gearing or other means may be used to rotate the same. Preferably, however, the rollers 11 and 13 are journaled and lubricated so that they will be rotated by the 30 frictional contact of the container 20 as it is pressed downward into contact with the applicator rolls 13. A suitable platform 16 is preferably positioned under the container 20 so as to prevent the container from inadvertently 35 dropping into the lake of glue beneath. The platform 16 may be suitably supported from the side walls of the glue box.

While certain novel features of the invention have been disclosed and are pointed out in the 40 annexed claims, it will be understood that various omissions, substitutions and changes may be made by those skilled in the art without departing from the spirit of the invention.

What is claimed is:

45 1. A merchandising package for individual articles including, inner protective members embracing said articles, an outer sleeve comprising a paperboard blank wrapped around said inner protective members, means for permanently securing said outer sleeve to said inner members, said means including tab portions extending from said outer sleeve and folded inwardly over a portion of the adjacent inner protective member, and means securing said tab portion to the adjacent 50 inner member, said outer sleeve having lines of weakness substantially coincident with the lines of division between said inner members permitting separation of said package into predetermined article-containing segments.

55 2. A merchandising container of the character described including, inner tubular sleeves each adapted to receive and contain an article, and an outer tubular sleeve telescoped over a plurality of inner tubular sleeves arranged in single alignment, means for fixedly securing said outer sleeve to said inner sleeve, said means including tab portions extending from said outer sleeve and folded inwardly to embrace the adjacent portion of an inner sleeve, and means permanently 60 securing each of said tab portions to an adjacent sleeve, said outer sleeve having lines of weakness substantially coincident with the lines of division between the inner sleeves permitting separation of said outer sleeve into predetermined sealed article-containing segments.

3. A merchandising package for a plurality of individual articles including in combination, an outer container of paperboard material having enclosing side walls, a plurality of inner containers of paperboard material each having enclosing side walls and an opening at one end thereof, each of said inner containers being located in said outer container with the open ends thereof covered and enclosed by a side wall of said outer container, means permanently securing said outer container to said inner container, said means including tabs each extending from said outer container and each folded inwardly through the opening in each of said inner containers to embrace the adjacent portion of the adjacent inner container, and means permanently securing each of said tabs to the adjacent inner container, said outer container having lines of weakness substantially coincident with the lines of division between said inner containers permitting separation of said package into predetermined article-containing segments.

4. A sealed merchandising package for separate vendable articles including a protective shell for each of said articles, and an outer container having enclosing side walls surrounding a plurality of said article containing shells, each of said shells having enclosing side walls and open ends with the open ends disposed in abutting relation to two opposite enclosing side walls of said outer container, means for fixedly securing said shells to said outer container which cannot be released without leaving visible evidence of tampering, said outer container having lines of separation substantially coincident with the lines of division between said inner shells whereby said outer container may be broken and separated into separate vendable segments each containing an article sealed therein, each of said lines of separation comprising a line of small perforations having a long cut line so interposed as to extend over a corner portion of said outer container whereby segment separation may be readily initiated and effected.

5. A merchandising package for light bulbs, batteries, radio tubes and similar articles including a plurality of inner containers each containing a vendable article, and an outer tubular container including enclosing side walls surrounding and enclosing said inner containers, means permanently securing each of said inner containers to said outer container including a tab extending from one of said containers folded over and fixed to an adjacent wall of the other container, said outer container having predetermined lines of weakness substantially coincident with the lines of division between said inner containers permitting separation of said package into predetermined segments so that each segment contains an article sealed therein.

6. A merchandising package for articles requiring test examination before delivery to the customer including a plurality of tubular inner containers each containing a vendable article, and an outer container enclosing said inner containers, means for permanently securing each of said inner containers to said outer container, said means including a tab portion extending from one of said containers folded over and sealed to an adjacent portion of the other container, said outer container having predetermined lines of perforations therein substantially coincident with the lines of division between said inner containers permitting separation of said outer container into predetermined sealed article-contain-

ing segments, and an opening in each of said segments through which the test end of the article may be ejected for test purposes.

7. A merchandising container for articles having a test end requiring test before delivery to the customer including inner tubular sleeves each adapted to receive and contain an article, an outer tubular sleeve telescoped over a plurality of inner tubular sleeves, means for fixedly and permanently securing said outer sleeve to each of said inner sleeves, said outer sleeve having lines of separation substantially coincident with the lines of division between the inner sleeves permitting separation of said outer sleeve into predetermined sealed article-containing segments, each of said lines of separation comprising a line of small perforations having a long cut line so interposed as to extend over a corner of the outer sleeve whereby segment separation may be readily initiated and effected, a test opening in one wall of each segment adjacent the test end of the article therein, and an ejection opening in the opposite wall of each segment into which an instrument may be inserted to eject the test end of the article out through the test opening in position available for test.

8. A merchandising package for light bulbs, batteries, radio tubes or similar articles requiring test examination before delivery to the customer including in combination, a tubular outer container of paperboard material having enclosing side walls and open ends, a plurality of inner

containers of paperboard material having enclosing side walls and open ends located in said outer container with the ends disposed in a direction transverse to that in which the ends of the outer container are disposed, said outer container having predetermined lines of separation substantially coincident with the lines of separation between said inner containers so as to permit said inner and outer containers to be broken into separate segments, each of said lines of separation comprising a series of small perforations having a plurality of long cuts interposed between said series so arranged that each long cut extends over a corner portion of the outer container whereby segment separation may be readily initiated and effected, means for fixedly securing each of said inner containers within said outer container so that each article is sealed within an article-enclosing segment when separated from the package, each segment having an inner side wall thereof positioned adjacent the test end of the article therein through which opening the test end may be ejected for test purposes without requiring removal of the article from the enclosing segment, and a complementary opening in another side wall of each segment positioned opposite the opening first-mentioned and into which complementary opening an instrument may be inserted to effect ejection of the test end of the article from the segment.

WILLIAM A. RINGLER.
